RUBBER HEEL

Charles Lamb, South Pasadena, Calif.

Application December 20, 1937, Serial No. 180,678

2 Claims. (Cl. 36—35)

This invention relates to the orthopedic art and particularly to heels made of rubber or other elastic material.

Extensive experimentation has been carried on from time to time with the object of providing a rubber heel which when used will tend to correct or mitigate the condition of fallen arches commonly known as flat feet. While engaged for many years in the manufacture of orthopedic rubber heels, I have made an intensive study of this problem, and have noted that one of the main differences of all these so-called orthopedic corrective rubber heels has been, first, that they did not supply a sufficient degree of resiliency in the main body of the heel and, secondly, that they were subject to a relatively rapid wearing down of the rear outer corners of the heels. The low degree of resiliency present in the main body of most of these heels had a tendency to defeat whatever advantage there is in a rubber heel in the way of correcting a tendency towards fallen arches or in relieving such a condition after it has become acute. I also noted that the rapid wearing down of the rear outer corners of rubber heels generally resulted in rendering these practically valueless after a relatively short period of use in so far as any corrective tendency they might have. This is because of the fact that when so worn down the fulcrum point in the heel moves forwardly so that instead of causing the shoe to pull down and rearwardly the metatarsals of the foot, so that the constrictive action of the tendons under the foot would lift the internal cuneiform and scaphoid structure of the instep upwardly, the shoe would tend in fact to resist the forward turning movement about the fulcrum in the heel and the tendency would be for the weight of the body to be thrown downwardly on the instep structure with the ultimate result of straining this.

Beginning with the observation of these facts, I proceeded through my experiments to the discovery that a new rubber heel having adequate resiliency in the main body thereof produces a distinctly beneficial effect resulting from corrective forces applied to the arch structure of the foot, tending to produce a high arch. Such a heel continues to produce this corrective effect moreover so long as it retains a substantially flat lower surface and a substantially uniform degree of resiliency from the extreme rear of the heel to the front thereof.

It is, therefore, an object of my invention to provide an orthopedic rubber heel which shall possess a substantially high degree of resiliency

throughout the main body thereof and which will tend, when used, to maintain over a relatively long period of use a substantially flat lower surface.

It is a further object of my invention to provide an orthopedic rubber heel the reaction to use of which is such that this heel will retain a substantially high degree of resiliency in the rear outer portion of the heel over a relatively long period of use. 5

Yet another object of my invention is to provide an orthopedic rubber heel, the reaction to use of which will be such as to maintain the original shape of said heel to an extent that the fulcrum about which the foot is caused to rock, 10 as this heel engages the ground, is maintained at a substantially maximum distance rearwardly, 15 as when the said heel is new.

A still further object of my invention is to provide an orthopedic rubber heel having the 20 characteristics above referred to and which is relatively inexpensive to produce.

The manner of accomplishing the foregoing objects as well as further objects and advantages will be made manifest in the following 25 description taken in connection with the accompanying drawing in which—

Fig. 1 is a side elevational view of a man striding and with the shoe of his foremost foot poised so that a rubber heel thereon is just about to 30 engage the ground.

Fig. 2 is a perspective view of the preferred form of my invention when embodied in a rubber heel for the right foot.

Fig. 3 is a vertical sectional view taken on the 35 line 3—3 of Fig. 2, and which shows the structure of said heel when it is new.

Fig. 4 is a diagrammatic cross-sectional view similar to Fig. 3 and illustrating the condition of 40 said heel after it has been subjected to a considerable period of use.

Fig. 5 is a diagrammatic sectional view of an ordinary rubber heel after it has been subjected to approximately the same amount of wear as 45 the heel of my invention illustrated in Fig. 4.

In searching for a solution to the problems referred to hereinabove, I discovered that the abnormal wearing away of the bottom face of a rubber heel in the area of maximum wear may be greatly decreased by the provision of material on 50 the other portions of the lower face of the heel which would tend to wear away more rapidly than the material used in the area of maximum wear.

As a preferred embodiment of my invention, 55

- therefore, I have provided a rubber heel 10 in which the main body 11 of the heel is composed of highly resilient rubber and which also has a relatively high resistance to abrasion. The body 5 of rubber 11 forms a relatively thick upper layer in the heel 10 of substantially uniform thickness throughout the heel except opposite the area of maximum wear 12 in which the rubber of the body 11 extends downwardly to the lower face of 10 the heel. Opposite the balance of the lower surface of the heel 10 I have provided a relatively thin inlay 13 of rubber which is less resilient than the body of rubber 11, and much more susceptible to abrasion.
- 15 In the manufacture of the heel 10 the body 11 and the inlay 13 are vulcanized into a single integral entity.

By virtue of the much greater susceptibility of the insert 13 to abrasion than the rubber of the 20 main body 11 of the heel 10, the insert 13 wears away more rapidly in use than that portion of the body 11 opposite the area of maximum wear 12. This results in the wearing away of the bottom portion of the heel 10 when the latter is in 25 use so as to maintain the bottom of the heel substantially flat as shown in Fig. 4. The wearing of the bottom surface of the heel in this manner results in maintaining a relatively uniform degree of resiliency throughout the length of the heel for 30 a relatively long period of use.

The advantages of this result are illustrated in the drawing by lines A—A, B—B and C—C in Figs. 3, 4 and 5 respectively, these lines indicating the planes of contact between the heel and the 35 ground which determine the fulcrum of rotation of the heel relative to the ground when the foot is planted on the ground and the weight of the body transferred thereto in walking rapidly as shown in Fig. 1.

- 40 In Fig. 3 it is seen that the plane A—A is such that the ball of the foot must be on the ground before the heel contacts the ground on this plane, thereby assuring that the fulcrum axis of the heel is disposed very close to the rear end of the heel. 45 This fact and the high degree of resiliency of the heel results in a rotational force being produced by the heel tending to force the front portion of the shoe downwardly. The resistance to this force by the compression and tension couples of 50 the bone and tendon structure of the foot stimulates a downward flexing of the metatarsals to bring the ball of the foot down and back and arch upward the central structure of the foot including the metatarsals, the internal cuniforms 55 and the scaphoid bones.

Owing to the uniform wearing of the bottom surface of the heel of my invention this heel after a considerable period of wear, as shown in Fig. 4, still retains the beneficial effects of a new heel on 60 the arch structure of the foot as above outlined.

While I have devised a number of embodiments

of the heel of my invention illustrated herein, some of which have a multiplicity of inserts in the bottom of the heel 10 and one of which I have disclosed in my co-pending application for U. S. Letters Patent, Serial No. 180,677 and filed here- 5 with, the present preferred embodiment may be made to substantially accomplish the benefits of the invention and yet is materially cheaper to manufacture than the other forms thereof owing to the fact that only a single insert 13 is re- 10 quired in the manufacture of the heel. This greatly simplifies the assembly of the molding rubber in the mold, and a high quality article of this type may thereby be produced at a much lower cost than where multiple inserts are re- 15 quired.

In Fig. 5 I have illustrated an ordinary rubber heel 20 as it appears after a considerable period of use, the line C—C indicating the plane of initial contact between a rear lower face 21 of the 20 heel and the ground. This plane is seen to be such as to throw the fulcrum about which the shoe rotates away forward towards the middle of the heel. This effects a tendency to rotate the shoe in exactly the opposite direction as a new 25 heel. In other words the heel 20 after engaging the ground on the plane of line C—C not only exerts no corrective force thereafter on the arch structure of the foot, but on the contrary produces a negative reaction applying undue strains 30 on the arch.

The foregoing comparison can be demonstrated by anyone by alternately wearing a pair of shoes having new rubber heels and a pair of shoes which are badly run down at the outward rear 35 portions thereof and carefully noting the exactly opposite reaction obtained.

What I claim is:

1. A heel comprising a body of rubber which includes: a base or upper layer of relatively high 40 resiliency and abrasion resistance, said base layer extending down to the lower face of said heel in the area of maximum wear; and a lower layer of uniformly and relatively low resiliency and abrasion 45 resistance, said lower layer covering the balance of the downwardly disposed areas of the lower face of said heel, said layers being vulcanized into a unitary body.

2. A heel comprising a body of rubber which includes: a relatively thick base or upper layer 50 of relatively high resiliency and abrasion resistance, said base layer extending down to the lower face of said heel in the area of maximum wear; and a relatively thin lower layer of uniformly and relatively low resiliency and abrasion 55 resistance, said lower layer covering the balance of the downwardly disposed areas of the lower face of said heel, said layers being vulcanized into a unitary body.

CHARLES LAMB. 60
